UNITED STATES PATENT OFFICE

CLYDE H. OVERMYER AND GEORGE J. OVERMYER, OF HARTFORD CITY, INDIANA

DESIGN FOR A PULL KNOB

Application filed March 17, 1930. Serial No. 34,948. Term of patent 14 years.

To all whom it may concern:

Be it known that we, CLYDE H. OVERMYER and GEORGE J. OVERMYER, citizens of the United States, residing at Hartford City, in the county of Blackford and State of Indiana, have invented a new, original, and ornamental Design for Pull Knob, of which the following is a specification.

Fig. 1 is a side elevation of a pull knob disclosing our new design;

Fig. 2 is a plan view thereof.

We claim:

The ornamental design for a pull knob as shown.

In witness whereof, we have hereunto set our hands at Indianapolis, Indiana, this 12th day of March, A. D. one thousand nine hundred and thirty.

CLYDE H. OVERMYER.
GEORGE J. OVERMYER.
